CLAIM

The ornamental design for a compact tablet computer case, as shown and described.

DESCRIPTION

FIG. 1 is a perspective view of a compact tablet computer case, showing the cover laid flat behind the case; FIG. 2 is a front elevational view thereof, showing the cover laid flat below the case; FIG. 3 is a rear elevational view thereof, showing the cover laid flat below the case; FIG. 4 is a right-side elevational view thereof, showing the cover laid flat below the case; FIG. 5 is a left-side elevational view thereof, showing the cover laid flat below the case; FIG. 6 is a bottom plan view thereof; and, FIG. 7 is a top plan view thereof, showing the cover laid flat below the case; FIG. 8 is a front elevational view of both the cover and the case of the compact tablet computer case, with the lower portion of the FIG. showing the cover laid flat and separated from the case and the upper portion of the FIG. showing the cover laid flat below the case;

FIG. 9 is a rear elevational view thereof, with the lower portion of the FIG. showing the cover laid flat and separated from the case and the upper portion of the FIG. showing the cover laid flat below the case;

FIG. 10 is a right-side elevational view thereof, showing the cover laid flat and separated from the case;

FIG. 11 is a left-side elevational view thereof, showing the cover laid flat and separated from the case;

FIG. 12 is a bottom plan view thereof at reduced scale, showing the cover laid flat and separated from the case; and, FIG. 13 is a top plan view thereof at reduced scale, showing the cover laid flat and separated from the case.

FIG. 14 is a front view of the cover of the compact tablet computer case, showing the cover laid flat and not showing the case;

FIG. 15 is a rear elevational view thereof, showing the cover laid flat and not showing the case;

FIG. 16 is a right-side elevational view thereof, showing the cover laid flat and not showing the case;

FIG. 17 is a left-side elevational view thereof, showing the cover laid flat and not showing the case;

FIG. 18 is a bottom plan view thereof, showing the cover laid flat and not showing the case; and,

FIG. 19 is a top plan view thereof, showing the cover laid flat and not showing the case;

FIG. 20 is a perspective view of the case, showing the cover folded under the case such that two edges of the cover are visible beneath the case;

FIG. 21 is a perspective view of the compact tablet computer case in one of the configurations allowed by the multitude of hook and loop fasteners, showing the cover as it appears when folded; and,

FIG. 22 is a perspective view of the compact tablet computer case in another one of the configurations allowed by the multitude of hook and loop fasteners, showing another view of the cover as it appears when folded.
